UNITED STATES PATENT OFFICE.

ALBERT E. LAMBERT, OF ALBANY, NEW YORK.

GARMENT.

Application filed October 15, 1921. Serial No. 507,949.

To all whom it may concern:

Be it known that I, ALBERT E. LAMBERT, a citizen of the United States, residing at Albany, in the county of Albany and State of New York, have invented certain new and useful Improvements in Garments, of which the following is a full, clear, and exact description, such as will enable others skilled in the art to which it appertains to 10 make and use the same.

This invention relates to garments, and more particularly in some of its details to a union garment especially adapted for under-wear.

15 It is an object of the invention to provide an improved garment which is capable of being put on or taken off readily and with little exertion or inconvenience to the wearer, and when in wearing position falls naturally 20 into place to clothe the wearer, and remains permanently in such position without gaping and without employment of buttons or other fastening means.

25 Another object is to provide a buttonless undergarment of improved construction, having an ample opening to enable the same to be easily placed in wearing position or removed.

30 Still another object is to provide a garment of the class mentioned, of superior durability, convenience and fitting qualities, which is simple in construction and inexpensive in manufacturing and cost.

35 Other objects will be in part obvious in connection with the following detailed description, and in part pointed out therein.

The invention accordingly consists in the 40 features of construction, combinations of elements and arrangement of parts which will be exemplified in the construction herein-after set forth, and the scope of the application of which will be indicated in the following claims.

In the accompanying drawings wherein an 45 illustrative but preferred embodiment of the invention is disclosed,

Figure 1 is a front elevation of the garment depicting the same as lying flat with the front and back portions in contact, and

50 Fig. 2 is a similar view showing the rear thereof.

Referring now to the drawing for a detailed description of the illustrative embodiment, an undergarment of the union variety is shown, having an upper body or vest portion 1 as distinguished from the

lower bifurcated portion 2. The vest or body portion is provided with arm openings 3, or sleeves may be employed, if desired. The front of the vest portion is provided with a round or a V-shape neck opening 4 in the upper portion thereof, and is preferably integrally extended at its lower edge across the waist-line into the front portion of the lower garment. By this construction the entire front of the garment may be made up from a single integral piece of material.

The rear of the vest portion is preferably made up of two pieces or sections of woven fabric, designated 5 and 6 respectively, stitched at the outer lateral edges to the adjacent lateral edges of the front of the garment, and at the top edges thereof stitched to the tops of the front pieces. This forms continuations of the front and rear portions 75 providing shoulder straps or supports for holding the garment in upright wearing position. The inner edge of the piece 5 is inclined downwardly from the left, as viewed in Fig. 2, toward the right of said figure, 80 terminating at the waist-line, and forming an outer substantially triangular-shaped flap, while the inner edge of the piece 6 is similarly inclined from the right of said figure, lying inside the flap 5 and forming 85 an inner triangular flap similar in construction and symmetrically disposed on the garment with respect to the flap 5. The overlapping portions of these flaps are discontinuous near the upper portion of the garment, that is, said flaps are in overlapped 90 relation only up to a point adjacent the upper portion of the garment providing a V-shaped neck opening 4' which is a continuation of the opening 4. The lower edges 95 of the two flaps 5 and 6 are stitched together as indicated at 7 and the inner lateral edges thereof terminate between the median line and respective sides of the garment but are otherwise unattached. A waist-band 8 extends transversely across the back of the garment at the waist-line, being preferably of elastic material such as knit fabric, or the like, and terminates at each end at the sides of the garment. The over-lapping stitched 100 lower edges of the flaps 5 and 6 are also stitched to the waist-band 8, preferably by the stitching 7 for securing the flap edges, while the lower edge of the waist-band is stitched at 9 to the upper edge of the lower 105 garment.

By means of this construction it will be

seen that the flaps are capable of moving apart so as to provide a large opening at the upper part of the garment to enable the same to be easily placed in wearing position 5 or to be removed. The waist-band lends a certain amount of resiliency to the garment, facilitating placing the same in wearing position and providing means whereby the garment conforms to the shape of the body in 10 various positions of the wearer. This is especially advantageous, inasmuch where the woven fabric employed in the general construction of the garment is not susceptible to a very great amount of stretching. 15 The interposition of the waist-band prevents straining, tearing or otherwise injuring the fabric and improves the wearing qualities of the garment and increases the comfort to the wearer. It is obvious that the waist- 20 band may be extended entirely around the garment, if desired, and it will also be understood that the flaps 5 and 6 may be disposed in front rather than behind, if considered desirable. 25 The nether garment is provided at the rear with an outer flap 10 preferably extending from the waist-band to the crotch and a co-terminous overlapping inner flap 11. The seat is preferably constructed quite full, this 30 arrangement of flaps being found comfortable and convenient. A front opening 12 is also provided, having outer and inner overlapping flaps with marginal reinforcements stitched together at their ends and are adapted 35 to automatically close the opening. The front opening is dis-continuous with the rear opening, an elongated crotch gusset 13 being interposed between the openings and stitched in position securing the opposite 40 lateral sides of the garment together at the crotch between the front and rear openings.

When the garment is in position, the overlying flaps 5 and 6 of the upper garment are effectually and automatically held in closed 45 position by engagement of the garment with the body of the wearer, the weight of the garment also tending to hold the flaps smoothly closed without gaping and without employment of buttons or other securing 50 means. The two flaps being symmetrically placed on the garment at the center of the body thereof, and secured together at their lower edges and to the waist-band, the stresses transmitted through the same to the 55 shoulders are equalized and the free lateral edges are held in close contact with each other, providing an effective, self-closing entry opening for the garment. This arrangement also provides a garment of superior fitting qualities and avoids binding 60 with resultant discomfort.

As many changes could be made in the above construction and many apparently widely different embodiments of this invention 65 could be made without departing from

the scope thereof, it is intended that all matter contained in the above description or shown in the accompanying drawings shall be interpreted as illustrative and not in a limiting sense. 70

It is also to be understood that the language used in the following claims is intended to cover all of the generic and specific features of the invention herein described and all statements of the scope of the invention, which, as a matter of language, might be said to fall therebetween. 75

Having described my invention, what I claim as new and desire to secure by Letters Patent, is:

1. A garment of the character described, having a body portion with an integral front having an opening therein, said garment also having a back portion secured at the sides of the garment to said front and co-operating therewith to form the vest or body portion, said back portion having freely over-lapping flaps united to each other substantially at the waist-line and being in over-lapped relation only up to a point adjacent the upper portion of the garment and being extended above the over-lapped parts and spaced apart near the upper portion of the garment, forming a rear neck opening in continuation of said front opening, the 90 extended portions of said flaps being united with the front of the garment to form shoulder supports adapted to hold the flaps in closed over-lapping relation when the garment is in wearing position, a waist-band 100 extending across the back of the garment and being united with said front and with the over-lapping portions of said flaps, and a nether garment having a rear portion united with said waist-band. 105

2. A garment of the character described, having a body portion with an integral front and with a neck opening therein, said garment also having a back portion secured to said front portion and having freely over-lapping flaps united to each other at the waist-line, a waist-band of resilient material extending transversely across said back portion, to one edge of which the united edges of said flaps are attached, the overlapping portions of said flaps being dis-continuous near the upper portion of the garment, forming a rear continuation of said front neck opening. 110

3. A garment of the character described, having a body portion with an integral front, having a neck opening therein, said garment also having a back portion secured to said front portion and having freely over-lapping flaps united to each other at the 120 waist-line, a waist-band of resilient material extending transversely across said back portion, to one edge of which the united edges of said flaps are attached, said garment having a bifur- 125

cated nether portion the front of which is integral with said body portion, the back being united with said waist-band.

4. A garment having an integral front for 5 the upper and lower portions thereof and being notched at its upper portion to provide a neck opening, a plurality of rear sections forming the rear of the body of the garment and being united at the sides of the 10 garment with the front to form the complete vest portion, said rear sections also having freely overlapping flaps secured at their lower edges substantially at the waist line and being held in closely overlapping 15 relationship to close the back of the garment by engagement with the body of the wearer, said flaps also being extended upwardly beyond the overlapping portions thereof and uniting with and forming continuations of the front sections over the 20 shoulders and being symmetrically disposed on the garment.

5. A union garment having vest and nether portions with front and rear sections, one 25 of said sections being made with a single integral piece of material being notched at its upper portion to provide a neck opening, a plurality of parts forming the other section of the body portion of said garment 30 and being united at the sides thereof with said first mentioned section to form the complete vest portion, said sections also having freely overlapping flaps symmetrically dis-

posed on the garment and secured together at their lower edges near the waist line and 35 being extended upwardly beyond the overlapping portions thereof and uniting with and forming continuations with the other said section over the shoulders, the lower secured edges of said flaps being united to 40 the upper edges of the nether garment.

6. A union garment having body and nether portion with front and rear sides, one of said sides being made of a single integral piece of material and being notched at its 45 upper portion to provide a neck opening, one of said sides of the garment having freely overlapping flaps secured together at their lower edges near the waistline and being extended upwardly beyond the overlapping 50 portions thereof and united with and forming continuations of the other side over the shoulders, and being symmetrically disposed on the garment, a waist-band of relatively resilient material extending across said garment and united at one edge with the overlapping edges of said flaps, and united at the opposite edge with the upper marginal portion of said nether garment. 55

In testimony whereof I affix my signature, 60 in the presence of two witnesses.

ALBERT E. LAMBERT.
